AIRPLANE DRIVE

Filed Oct. 24, 1927

INVENTOR.
NORH MOSER.

BY.

H. A. Dickman
ATTORNEY.

UNITED STATES PATENT OFFICE.

NOAH MOSER, OF LONG BEACH, CALIFORNIA.

AIRPLANE DRIVE.

Application filed October 24, 1927. Serial No. 228,198.

An object of my invention is to drive an airplane by reducing the air pressure in front of a plate secured to the fuselage.

Another object is to provide the novel drive as recited above on a plane of standard construction, having the usual engine therein.

A further object is to drive an airplane by means of a rotor which rapidly moves the air in a radial line away from rotor and away 10 from the front surface of a plate secured to the plane.

Other objects, advantages and features of invention may appear in the accompanying drawings, the subjoined detailed descriptions, and the appended claims.

In the drawing—

Fig. 1, is a side elevation of an airplane with my drive mounted thereon.

Fig. 2, is a front elevation of one form of 20 drive.

Fig. 3, is a front elevation of another form of drive.

Fig. 4, is a fragmentary side elevation of 25 a plane upon which my novel drive is mounted.

Referring more particularly to the drawing.

The numeral 1, indicates an airplane of well known and usual construction comprising the usual fuselage 2, wings 3, engine (not shown), and drive shaft 4, from the engine.

The circular plate 5, is secured to the front of the fuselage 2, forwardly of the engine and the drive shaft 4, extends through said 35 plate.

An impeller 6, is secured to the shaft 4, and is positioned forwardly of the plate 5 and rotates as closely as is practical to the front face of the plate; the impeller 6, is so formed 40 as to rapidly move the air in a radial direction from the center of the impeller and this rapid movement of the air causes a reduced air pressure forwardly of the plate 5, thus causing the plane to move due to the normal 45 air pressure back of the plate. The impeller

6, may be formed with curved arms 7, as shown in Figure 2, or I may provide a plurality of arms 8, as shown in Figure 3, and if desired I may provide a conical deflector 9, which is secure to the impeller and serves 50 to deflect the air outwardly away from the center or ineffective part of the impeller.

It will be evident that the lift of the plane itself is affective in the same way as with the now well known plane, namely, by means of 55 the wing or wings 3.

My invention relates merely to the method of rapidly carrying the plane forwardly in the air. While I have shown my invention as applied to the single engine plane it will 60 be evident that the same construction and arrangement can be applied to airplanes having a plurality of engines.

Having described my invention, I claim:

1. In combination with an airplane including a fuselage, wings and engine, a plate secured to said fuselage forwardly of the engine, and an impeller rotatable by the engine and positioned immediately in front of said plate, the outer ends of said impeller being 70 curved away from the direction of rotation thereof so as to move the air outwardly in a radial direction and away from the front of said plate.

2. In combination with an airplane including a fuselage, wings and engine, a plate secured to said fuselage forwardly of the engine, and an impeller rotatable by the engine and positioned immediately in front of said plate, the outer ends of said impeller being 75 curved away from the direction of rotation thereof so as to move the air outwardly in a radial direction and away from the front of said plate, and a conical deflector extending 80 forwardly from said impeller and secured thereto, said deflector covering only the central portion of the impeller.

In testimony whereof I affix my signature.

NOAH MOSER.
